US00D484923S

(12) **United States Design Patent** (10) Patent No.: **US D484,923 S**
Wai-Kei (45) Date of Patent: ** Jan. 6, 2004

(54) **ELECTRONIC LEARNING AID HOUSING FACE**

(75) Inventor: **Kenneth Ko Wai-Kei**, Kowloon (HK)

(73) Assignee: **VTech Electronics Limited**, New Territories (HK)

(**) Term: **14 Years**

(21) Appl. No.: **29/146,064**

(22) Filed: **Aug. 2, 2001**

(51) LOC (7) Cl. **21-01**

(52) U.S. Cl. **D21/398**; D21/409; D21/475

(58) **Field of Search** D21/324, 329, D21/398, 405, 409, 468, 475, 476, 483, 513, 515; D19/60; 446/143, 484; 434/156, 159, 161, 169, 201, 202, 309, 393
